UNITED STATES PATENT OFFICE.

WILLIAM H. LUDEN, OF LANCASTER, PENNSYLVANIA, ASSIGNOR OF ONE-FOURTH TO
MILES L. DAVIS, OF LANCASTER, PENNSYLVANIA.

DEVICE FOR FEEDING IRON OR STEEL TO SPIKE, NUT, OR BOLT MACHINES.

No. 910,139.

Specification of Letters Patent.

Patented Jan. 19, 1909.

Application filed June 3, 1905. Serial No. 263,548.

To all whom it may concern:

Be it known that I, WILLIAM H. LUDEN, a citizen of the United States, residing at Lancaster city, in the county of Lancaster and 5 State of Pennsylvania, have invented certain new and useful Improvements in Devices for Feeding Iron or Steel to a Spike, Nut, or Bolt Machine, of which the following is a specification, reference being had therein 10 to the accompanying drawing.

My invention relates to improvements in a device for feeding iron or steel to a spike nut or bolt machine.

The object of my invention is to provide a 15 device of this character which is adapted to be used in connection with any ordinary nut bolt or spike machine, and is operated by the same.

A further object of this invention is to 20 provide a device of this character which is adapted to receive material of different thicknesses and widths.

Another object of my invention is to provide a machine of this character so constructed that should anything happen to the same, the machine which it feeds would continue to operate and the feeding machine would automatically stop its feeding mechanism and thus the same would not be 30 come broken or otherwise put out of commission by the feeding mechanism not properly working.

In the accompanying drawings, Figure 1, is a side elevation of my improved feeding machine, showing the main operating lever omitted. Fig. 2, is a side elevation of my improved machine looking from the opposite direction. Fig. 3, is an enlarged detached end view of the adjustable supporting heads and the operating lever. Fig. 4, is a vertical sectional view taken on the line $z-z$ of Fig. 1. Fig. 5, is a vertical sectional view taken on line $y-y$ of Fig. 1. Fig. 6, is an enlarged side elevation partly broken away. Fig. 7, is a top plan view showing the clamping members and one of the same partly broken away for showing the spring members for forcing the jaws inwardly. Fig. 8, is an enlarged horizontal sectional view showing the wedging members in their operative position with the clamping member. Fig. 9, is a detail side view of the guide adjusting member. Fig. 10, is an enlarged

detail end view of the guide-adjusting members. Fig. 11, is an enlarged side view of 55 the guide table at the rear of the main table. Fig. 12, is a top plan view of the guide table showing the spring connection.

Referring now to the drawings, 1 and 2 indicate the legs of the machine which as 60 shown, are at the ends, and are arch-shaped as shown in Fig. 3 of the drawings, and resting upon said legs are the heads 3 and 4 which are vertically adjustably supported. The said heads as shown, are provided with 65 downwardly-extending screw-threaded bolts 5 which pass through openings in the upper ends of the legs 1 and 2, and on said bolt above the legs are nuts 6 and below said legs on the bolt are nuts 7 which firmly hold 70 the heads on the legs, and allow the same to be vertically adjusted. The upper ends of said heads 3 and 4 support the table 8, and thus it will be seen that said table and the feed mechanism may be vertically adjusted 75 to accommodate itself to the machine it is feeding. It being understood that this feeding machine is placed between the furnace and the bolt, nut, or spike machine, and the same being of different heights, thus it is 80 necessary to have the table and feeding mechanism vertically-adjustable. The said heads 3 and 4 adjacent their lower ends are provided with inwardly extending shoulders 85 9 and 10, which are adapted to support the horizontal bars 11 and 12 upon which the feeding mechanism is slidably mounted, as hereinafter more fully described. The ends of said horizontal bars 11 and 12 are bifurcated at 13, and adapted to receive the 90 upwardly-extending members 14 carried by the shoulders 9 and 10 carried by the heads. The said shoulders are provided with screws 15 which pass therethrough from the underside and bear against the underside of the 95 bars 11 and 12, and thus the said bars may be vertically adjusted to take up the wear, etc. which is bound to occur in a device of this character, and thus the clamping jaws are held in their relative position in respect 100 to the table 8 as will be hereinafter fully described. Slidably mounted on said bars 11 and 12, is the slide-box 16 which has secured to the outer sides thereof the plates 17 by means of bolts or screws 18, and pivotally 105 mounted in each side of said slide box are the

grip members 19 and 20. The upper ends of said grip members 19 and 20 are so shaped that they extend outwardly around the table 8, and at the extreme upper ends 5 are provided with inwardly extending portions 21 which extend over the outer edges of the table 8.

It will be understood that the table 8 is for supporting the metal bars as they come 10 from the furnace and are fed to the bolt, rivet or spike machine. The said grip members 19 and 20 are pivotally connected to the slide-box 16 by means of bolts 22, and the lower ends of said members extend down- 15 wardly adjacent or in a line with the upper ends of the feet 1 and 2. The said lower end of said clamping members have bolted thereto by means of bolts 23, the wedge-shaped members 24 between which is forced 20 the wedge 25 which forces the lower end of the gripping members apart, and thus cause the upper ends to close and grip the metal, which will be hereinafter more fully described.

25 The upper ends of the grip members as shown in Fig. 5, are provided with recesses 26 in which rest the elongated spring tension gripping blocks 27, said gripping members having transverse openings 28 in communication with the said recesses 26, and each gripping block 27 is provided with two inwardly-extending pins 29 and 30 which are provided with coil springs 31, which have one end bearing against the gripping 35 blocks and the opposite ends bearing against the inner end of the recess 28, thus causing the said blocks to be normally outwardly spring-held, which allows of the said jaws to at all times grip the bars of metal, regardless of the slight variations in the width or 40 thickness of the same. The gripping blocks 27 on the inner faces are provided with rollers 27' which are adapted to engage the bar being fed to the machine, and thus when the gripping blocks are released, and move backwards to take another hold, the bar being 45 fed is guided by the rollers and yet there will be little or no friction.

50 Pivots connected to the upper ends of the slide box 16 by a bolt 32, is a downwardly-extending lever 33 which has pivotally connected to its lower end by the bolt 34, a horizontal lever 35 which passes between the lower ends of the grip members 19 and 20, and the opposite end is pivotally connected to the lower end of the lever 37 by means of a bolt 36. The said upwardly-extending lever 37 is intermediately pivoted at 38 to the lower edge of the slide-box 16, 55 and the upper end of the said lever 37 is pivotally connected at 39 to a second horizontal lever 40, which extends across the machine and passes through an elongated opening 41 in the upper end of the portion 16' of 60 the slide-box 16, and has secured thereto a

cross-head 42 which rests upon the slide bars 11 and 12 and is adapted to slide thereon.

The vertically disposed lever 33 has connected thereto an inwardly-extending horizontal bar 43 which carries at its inner end 70 the wedge 25 heretofore described, and thus as the lever 33 is moved in or out, the wedge moves between the wedge-shaped members 24 carried by the grip jaws 19 and 20, and the upper ends are forced together to grip 75 the metal bars. The extreme lower ends of the grip jaws are provided with screws 44 to which is secured the ends of a coil spring 45 which normally holds the lower ends of the jaws together and separates the upper 80 ends when the wedge 25 is in its outward position.

Secured to the floor or base upon which the machine is mounted adjacent the leg 2, is a journal bearing 46 in which is mounted 85 a horizontal shaft 47. The said shaft has at the right of the machine an upwardly-extending arm or lever 48 which is rigidly secured to the said shaft and adapted to oscillate the same. The upper end of said lever has pivotally connected thereto at 49 the horizontally-extending operating arm 50 which extends forward to the bolt screw or spike-making machine and is operatively connected thereto, and through the medium 90 of which the whole feed machine is operatively connected. The said shaft has rigidly connected thereto the upwardly-extending arm which is provided with the enlarged horizontal portion 52, which is provided centrally 95 with the upwardly-extending standard 53, and pivotally connected to the inner end of said enlarged horizontal portion 52 at 54, is the upwardly-extending operating arm 55. The said arm passes through a loop 56 100 carried by the upper end of the standard 53, and the said loop serves as a guide and also as a stop for the operating lever 55. The said standard 53 is provided with a rigid outwardly-extending arm 57 which is provided at its outer end with a plate 58 through 105 which the rod 59 is free to pass. The said rod at its outer end is provided with a stop 59' to prevent the same from being drawn out from within the plate 58. The upper 110 end of said rod is pivotally connected to the operating lever 55 at 60, and surrounding said rod is a coil spring 61 which has one end bearing against the arm 57, and the upper end bearing against the operating lever 55, 115 which is of such strength as to normally hold the lever 55 in its position shown in Fig. 1. This position as shown, is up against the standard 53, and under normal conditions is formed as a part of the same and rocks back and forth with the same as it is rocked by the shaft 47, which is operated as heretofore described. The upper end of said lever 55 adjacent its upper end is provided with a catch 62 which is pivoted at 63 to the 120

130

said lever, and the outer end of the said catch is provided with a slot 64 which is adapted to drop over the pin or bar 65 carried by the slide head, and thus the slide-box is reciprocated and the clamping jaws operated as said lever 55 is rocked. The outer end of the catch 62 is provided with a handle 65 by means of which the catch is raised and the lever disconnected from the feeding mechanism. By this arrangement, it is readily seen that the lever may continue to move and the feed mechanism uncoupled therefrom should it be desired to stop the same for any reason whatever.

When the lever 55 is coupled by means of the catch 62 to the cross-slide head 42, the same is moved on the bars 11 and 12 which draws the upper end of the lever 37 in the direction indicated by arrow in Fig. 6, and the lower end of the lever 33 in the direction indicated by arrow, same figure, through the medium of the bar 40. The movement of the lever 33 as above stated, moves the wedge 25 between the wedge blocks 24 carried by the lower end of the grip members 19 and 20, and thus the upper ends are brought together and the metal bar firmly clamped between the same. The continued movement of the cross-head 42 draws the whole slide box forward in the direction indicated by arrow, and thus the metal bar is fed forward to the machine. When the lever 55 has reached its limit of movement and the same starts backward through the medium of the levers 40, 39, 35 and 33, the wedge is first moved from between the wedge blocks and the spring 45 releases the clamp jaws from the metal rod and the continued movement of the lever causes the slide-box to slide up the bars 11 and 12 and return to its original position ready for another operation of carrying the metal bar forward.

In order to adjust the movement of the levers 40, 39, 37, 35 and 33, before the movement of the slide-box is commenced for the purpose of causing the grip members to move more or less for clamping bars of different widths, I provide the bar 40 with a screw-threaded portion 66 which screws into a nut 67 carried by the lever 37, and thus by shortening or lengthening the bar 40 the movement of the wedge 25 is changed, which in turn regulates the inward movement of the clamping jaw. In order to more certainly limit the movement of the clamping jaws, I provide the plates 17 with screws 68 which are in the path of movement of said jaws, and thus by screwing the same in or out, the absolute movement of the clamping jaws is regulated.

It will be understood that the metal bars are not entirely supported by the table 8, but only rest upon the same when the grip jaws or members are moving back to take another hold, and the bar is raised slightly

from the table when the grip jaws take hold of the same, and thus there is less wear upon the table. Below the table 8 I place a pan 69 which is adapted to catch the scales from the heated metal, and prevent the same from entering the working part of the machine.

The rearward ends of the spring-pressed grip blocks 27 are slightly beveled at 70 which allows the same to more readily receive the end of a bar as it starts through 75 the machine. In order to absolutely prevent the bar of metal from any reason riding up from between the grip blocks, I provide a roller 71 which is supported in a bracket 72 which is carried by the table 8. The forward ends of each of said grip blocks are provided with guide bars 73, which serve as additional guides for the metal bar being fed.

At the forward end of the table 8 I provide an additional guide 73' which is pivotally connected to the table 8 by a bolt or rod 74, and said table or guide I provide with the upwardly extending members 75 and 76 and thus the bar is held between the same 90 as it is being cut off by the machine. The said guide moves in the direction indicated by arrow in Fig. 12, and is normally pushed in that direction by a spring 77. The guide 73' being pivoted as before described, allows 95 of a sidewise movement of the bar of iron being cut, caused by many reasons within the machine to which it is being fed, and will prevent any injury to any part of my feeding machine.

It will be seen in the operation of this device, should anything happen to the gripping mechanism so that the same could not be moved or slid upon the bars 11 and 12, in order to prevent the breaking of any parts, I 105 have provided the spring connection 61. This will allow the standard 53 and the arm 54 to continue to oscillate and the arm 55 being pivoted at its lower end, will remain in its position, thus preventing the machine 110 from breaking other parts, which would be the case if there was a rigid connection between said lever and oscillating member.

The upper end of the clamping jaw 20 has pivoted at 78, the latch 79 which is provided adjacent its opposite end with a slot 80, and the extreme end is provided with a handle 81 by means of which the same may be swung around so that the slot 80 will receive the pin 81 carried by the upper end of 120 the clamping jaw 19, and thus the two jaws will be locked together and the feeding of the machine stopped. This locking of the two jaws together, is precisely the same as if the machine had been stopped by gripping means not properly feeding, and thus the feeding will be stopped, but the machine continues to run, as heretofore described. By this structure it will be readily seen that the feeding of the bar can at any time be 130

stopped without stopping the remainder of the machine.

Having thus described my invention, what I claim and desire to secure by Letters Patent, is:-

1. A machine of the character described, comprising a frame, horizontal tracks supported by the frame, clamping jaws slidably mounted thereon, a lever operatively connected to said clamping jaws, said lever pivoted at its lower end to an oscillating member, an outwardly extending arm rigidly carried by the oscillating member, and a spring connection between said arm and lever.

2. A machine of the character described, comprising a frame, horizontal tracks carried by the frame, clamping jaws slidably mounted on said tracks, a series of levers pivotally connected together and connected to the clamping jaws for sliding the jaws on the track, and simultaneously clamping said jaws together, a lever for operating said series of levers, an outwardly-extending arm rigidly carried by the operating lever, and a spring connection between said arm and series of levers.

3. A machine of the character described, comprising a frame, a horizontal supporting table carried thereby, a track carried by the frame below the table, a sliding box carried by the track, clamping members carried by the box, and extending over the table, and a series of levers pivoted together and connected to the clamping members and adapted to operate the clamping members during one movement of the box.

4. A machine of the character described, comprising a frame, a sliding box on said frame, a table above said box, clamping jaws carried by the box and extending over the table, means for reciprocating said box, and means whereby the reciprocation of said box closes said jaws, and means for opening said jaws.

5. A machine of the character described, comprising a frame, clamping jaws slidably mounted thereon, a lever operatively connected to said clamping jaws, said lever pivoted at its lower end to an oscillating member, an outwardly extending arm rigidly carried by the oscillating member, and a spring connection between said arm and lever.

6. A machine of the character described, comprising a frame, clamping jaws slidably mounted thereon, a lever operatively connected to said clamping jaws, said lever pivoted at its lower end to an oscillating member, and an upwardly extending member rigidly carried by the oscillating member and against which the operating lever is normally spring held.

7. A machine of the character described,

comprising a frame, clamping jaws slidably mounted thereon, a lever operatively connected to said clamping jaws, said lever having its lower end pivotally connected to an oscillating member, an upwardly-extending arm rigidly carried by the oscillating member, an elongated loop carried by said member and

8. A machine of the character described, comprising a frame, a table carried thereby, a slide-box carried by the frame, clamping jaws carried by the slide-box, a pivoted lever adjacent said slide-box, means for operating said lever, and a pivoted catch carried by the lever and adapted to catch over said slide-box.

9. A machine of the character described, comprising a frame, clamping jaws slidably mounted on the frame, a lever adjacent said clamping jaws, and a pivoted catch carried by the lever and adapted to lock the clamping jaws thereto.

10. A machine of the character described, comprising a frame, clamping jaws pivotally carried by said frame, means operated by the machine for operating said jaws, a spring connection between the jaws and the connection with the machine, a pin carried by the upper end of one of said jaws, a swinging catch pivotally carried by the upper end of the other jaw and provided with a slot to receive the pin of the other jaw, and locking the two jaws together whereby the spring connection allows the machine to continue to run and the jaws to remain stationary.

11. A machine of the character described, comprising a frame, clamping jaws slidably mounted thereon, a lever operatively connected to said clamping jaws, an oscillating member carried by the frame, said lever pivoted at its lower end to said oscillating member, means on said oscillating member for operating said lever, and a spring connection between said lever and operating means, whereby the lever will remain at rest and the operating mechanism continue to run.

12. A machine of the character described, comprising a frame, a table carried by the upper end of the frame, a track carried by the frame below the table and parallel therewith, a sliding box carried by the track, clamping jaws intermediately pivoted to the sliding box, a lever operatively connected to said clamping jaws, said lever having its lower end pivotally connected to an oscillating member, an upwardly-extending arm rigidly carried by the oscillating member, an elongated loop carried by said member and

through which passes the lever, a horizontally-extending arm carried by the oscillating member, a rod carried by the lever and loosely passing through the outer end of said 5 horizontal bar, and a coil spring surrounding and normally holding the lever up against the upwardly-extending arm.

In testimony whereof I affix my signature in presence of two witnesses.

WILLIAM H. LUDEN.
